UNITED STATES PATENT OFFICE.

THOMAS L. LEE, OF ROCHESTER, NEW YORK, ASSIGNOR TO NORTH EAST ELECTRIC COMPANY, OF ROCHESTER, NEW YORK, A CORPORATION OF NEW YORK.

BRUSH RIGGING.

Application filed March 9, 1922. Serial No. 542,453.

To all whom it may concern:

Be it known that I, THOMAS L. LEE, a citizen of the United States, residing at Rochester, in the county of Monroe and State of New York, have invented certain new and useful Improvements in Brush Rigging; and I do hereby declare the following to be a full, clear, and exact description of the invention, such as will enable others skilled in the art to which it appertains to make and use the same.

This invention relates to brush-riggings of the type in which the brushes slide in stationary brush-guides and are pressed against the commutator by spring-pressed swinging arms.

One object of the invention is to produce a brush-rigging, of the type in question, in which the several parts are of simple and inexpensive form and are adapted for easy and secure assembly. A second object of the invention is to produce a brush-rigging in which the stationary members may be used interchangeably for opposite directions of operation. A third object of the invention is to provide means for equalizing the pressure and reducing the friction of the spring-pressed arm against the end of the brush.

To the foregoing ends the invention consists in the brush-rigging of which a specific form is hereinafter described, as it is defined in the appended claims.

In the accompanying drawings Fig. 1 is an axial elevation of the end of a dynamo-electric machine, looking from the inside, provided with brush-rigging embodying the present invention. Figs. 2 and 3 are plan-views of two of the brush-guides and associated parts, arranged for opposite directions of operation. Fig. 4 is a horizontal sectional view of the parts shown in Fig. 2. Fig. 5 is a side-elevation, on an enlarged scale, of one of the spring-pressed arms; and Fig. 6 is a section on the line 6-6 in Fig. 5, showing also a part of a brush associated with the arm.

The invention is illustrated as embodied in a machine provided with three brush-guides. Each guide is a U-shaped sheet-metal member formed integrally and comprising a middle-part 10 and two parallel arms 11. The inner surface of the part 10 is flat and provides a bearing-surface against which a brush may slide.

The arms 11 are perforated at their ends, to receive a bolt 12, which constitutes a post for supporting the brush-guide. The brush-guide is attached to a stationary support in the form of a plate 13 (as shown in Figs. 2, 3 and 4) which plate is fixed, at the end of the machine, in a position normal to the axis thereof. The brush-guide is insulated from the plate or support 13 by insulating-material 14 interposed between these parts, and the bolt is tightened so as to clamp the brush-guide firmly against the insulating-material and thus secure the brush-guide in stationary position.

To prevent the arms of the brush-guide from being bent together by the tightening of the bolt, a bushing 15 is placed upon the bolt between the arms. This bushing serves also as means for engaging and clamping a perforated lug 16 constituting part of a connector 17, conveniently adapted for use in connecting the brush with the circuit-conductors of the machine, in the usual manner.

To anchor the brush-guide securely against swinging movement about the bolt 12, a screw 18 is used, this screw engaging one or the other of two tapped holes 19 provided in the two arms of the brush-guide.

The brush is pressed towards the commutator by an arm 20, which is fixed to a sleeve 21 arranged to turn on the bushing 15. A coiled spring 22 surrounds the sleeve, and one end of the spring engages the brush-guide, while the other end, 23, may be engaged alternatively with three hooks 24 on the arm 20. The pressure against the brush may thus be adjusted. To eliminate friction from the movement of the arm 20, it has been found desirable to prevent engagement between the sleeve 21 and the coils of the spring, as far as possible, and accordingly the sleeve is provided with a flange 25 which supports the spring-coils near one end, while the other end-coils are supported by a washer 26 at the end of the sleeve.

It is common to provide an anti-friction roller at the end of the spring-pressed arm which engages the brush. A feature of the present invention resides in the use of two such rollers, lying on opposite sides of the arm. These rollers, 27, are connected by a pivot 28 passing through a perforation in the arm, and the parts are fitted loosely, so that sufficient tilting may occur to permit

both rollers to engage the brush with substantially equal pressure, regardless of inaccuracies in the form of the several parts. In this way the brush is caused to engage the commutator with substantially uniform pressure across its face, while the construction avoids the necessity of a bifurcated arm, such as is commonly found where only one roller is used, engaging the middle of the brush.

In the illustrated machine three brushes are used, the brushes 29 being the main brush, and the brush 30 an auxiliary brush. The latter is mounted on a plate 31 which is angularly adjustable, as is common in such machines. To compensate for the thickness of the plate 31 and bring the brushes all to the same plane, spacers 32 are interposed between the plate 13 and the guides of the brushes 29.

The brushes are held against the middle parts of the guides by the reaction of the pressures against their beveled ends, in the usual manner of a reaction brush-holder, but security against accidental displacement is afforded by the provision of lugs 33 which are cut and bent from the sheet-material at the sides of the guides.

Figs. 2 and 3 show how, owing to the symmetrical form of the brush-guide, the same guide, post, insulation and other parts may be used whether the brush is to be inclined in one or the other direction. Only the spring, the spring-arm and the connector are different as shown in these two figures.

The invention is not limited to the embodiment thereof hereinbefore described, and illustrated in the drawings, but it may be embodied in various other forms within the scope of the following claims.

The invention claimed is:

1. Brush-rigging comprising, in combination with a base-member normal to the axis of a dynamo-electric machine: a reversible U-shaped brush-guide with a flat bearing-surface on the inside of its middle-portion; a post connecting the ends of the arms of said brush guide and drawing the guide as a whole toward the base-member; insulating

material interposed between the brush-guide and the base-member; an arm pivotally mounted on the post and adapted to engage the brush; and a spring engaging said arm and coiled around the post.

2. Brush-rigging comprising: a brush-guide; a spring-pressed pivotally-mounted arm with a bearing opening near its free end; and two rollers, on opposite sides of the arm, connected by an axis passing loosely through said bearing-opening and free to tilt therein.

3. Brush-rigging comprising: a U-shaped sheet-metal brush-guide with perforations at the ends of its arms; a bolt passing through said perforations and adapted to secure the brush-guide to a support; a bushing surrounding the bolt and interposed between the arms of the brush-guide; a sleeve surrounding and rotatable upon the bushing; an arm projecting rigidly from the sleeve and adapted to engage a brush supported by the brush-guide; and a spring engaging the arm and coiled around the sleeve.

4. Brush-rigging comprising: a U-shaped sheet-metal brush-guide with perforations at the ends of its arms; a bolt passing through said perforations and adapted to secure the brush-guide to a support; a bushing surrounding the bolt and interposed between the arms of the brush-guide; and a terminal-connector having a part surrounding the bolt and interposed between one end of said bushing and the adjacent arm of the brush-guide.

5. Brush-rigging comprising: a U-shaped brush-guide with a flat bearing-surface on the inside of its middle part, the brush-guide being formed integrally of sheet-metal and being perforated at the ends of its arms; a post connecting the ends of the arms and adapted to support the brush-guide; and a lug cut from the metal at one side of the brush-guide and bent inwardly substantially parallel with the middle part of the brush-guide, in position to retain a brush against said bearing-surface.

THOMAS L. LEE.
